LINK CHAIN FOR A BRACELET OR SIMILAR ARTICLE

Michael Chernow, New York, N. Y.

Application April 5, 1954, Serial No. 29,840

Term of patent 7 years

(Cl. D45—4)

To all whom it may concern:

Be it known that I, Michael Chernow, a citizen of the United States and residing at New York, in the county of New York and State of New York, have invented a new, original, and ornamental Design for a Link Chain for a Bracelet or Similar Article, of which the following is a specification, reference being had to the accompanying drawing, forming part thereof, and in which:

Fig. 1 is a fragmentary plan view of a link chain for a bracelet or similar article, showing my new design, the links shown in full lines being repeated throughout the length thereof as indicated by the dot and dash lines;

Fig. 2 is a side elevational view thereof taken along line 2—2 of Fig. 1; and

Fig. 3 is a sectional view thereof taken along line 3—3 of Fig. 1.

I claim:

The ornamental design for a link chain for a bracelet or similar article, substantially as shown and described.
